WINDOW CLEANING DEVICE

Filed Aug. 21, 1947

INVENTOR.

HARRY SLAVIN.

BY

Burton & Parker
ATTORNEYS

ciated cleaning element 20 laterally relative to the arm 12.

Means is carried on the closed end section 32 which yieldingly urges the closed end section away from the arm 12. This means comprising a metal strap 34 having inherent resilient characteristics and so formed as to project beyond the opposite ends of section 32. The opposite projecting ends of the strap 34, referred to at 36—36, are bent or curved toward the arm 12 and contact or bear upon the outer face of the arm. Preferably, these projecting end portions following their contact with arm 12 are curved outwardly away therefrom as indicated in Figs. 1 and 2. Suitable means, such as the screws members 38 may be employed to secure the intermediate portion of the strap 34 to the closed end section 32. Normally, resilient end portions of the strap 34 will act to space the closed end section 32 away from the arm 12 and thus draw the cleaning element 20 away from the opposing cleaning element 16. When in use upon a window pane, as will be described in more detail hereinafter, the position of the parts illustrated in full lines in Figs. 1 and 2 will occur, thus bringing the two cleaning elements into substantially juxtaposed relation.

The metal strap 34, in combination with the closed end section 32 and the arm 12, form a handle which is grasped by the hand of the operator. When the handle is tightly gripped or squeezed, the intermediate portion of the strap 34 and the arm 12 are moved toward one another against the yielding resistance of the projecting end sections 36—36 and assume the position shown in Figs. 1 and 2. As a result of this squeezing action, the cleaning element 20 is moved by member 24 toward the opposite cleaning element 16. In use, the U-shaped structure formed by arms 10 and 12 and the closed end 14 thereof is mounted in a window opening so that the arms overlap upon opposite sides of a window sash indicated at 40. The wiping elements are brought into position on opposite sides of the window pane 42 and when the handle is tightly gripped by the operator, the cleaning elements 16 and 20 will be compressed into engagement with the opposite surfaces of the window pane. The dotted outline of the device in Fig. 1 illustrates an initial position of the parts prior to the squeezing operation. Thereafter, upon squeezing of the hand which grasps the handle, the frame member 24 will be moved inwardly toward the window pane and into engagement therewith.

In the operating position, it is desirable to lock the cleaning elements in engagement with the window pane. For this purpose, there is provided a releasable locking detent comprising a plate member 44 which is hinged at 46 to the edge of one of the side sections of the member 24. The plate 44 is provided with two downwardly turned flanges 48 and 50 which, when the detent is swung to the position indicated in Fig. 2, will overlap upon the strap 34 and the arm 12, respectively, as shown in Fig. 4. The flanges 48 and 50 are so spaced apart that when in this position they hold the parts of the handle in the tightly gripped position imparted thereto by the operator. Associated with the hinge is a spring which yieldingly urges the detent to its locking position. Referring to Figs. 2 and 5, such a spring is illustrated as being in the form of a wire member 52, having its intermediate portion wrapped around the hinge pin 54 and

its extremities respectively bearing against the adjacent side of the member 24 and against the upper and outer surface of the detent plate 44. The extremities of the spring member 52 tend to urge the detent to its locking position shown in the drawings. When the device is moved into position upon opposite sides of a window pane, the detent is shifted into unlocking position in order to allow the resilient strap member 34 to space the cleaning elements 16 and 20 apart from one another sufficiently to clear the sash 40 of the window. Thereafter, when the handle is tightly gripped by the operator to force the cleaning elements into engagement with the window pane, the detent may be allowed to return to its locking position, holding these elements in close engagement with the pane.

Fig. 3 illustrates a modification of the invention wherein there is substituted for the cleaning elements 16 and 20, wiper blades 56 and 58. These blades are preferably formed of resilient material, such as rubber, and are mounted respectively upon base members 60 and 62, which in turn, are secured to the inner faces of the arms 10 and 12. The use of the device of Fig. 3 is similar to the embodiment of the invention previously described.

What I claim is:

1. A window cleaning device comprising, in combination, a pair of arms extending in spaced generally parallel relation to one another and joined at one of their ends to form a U-shaped supporting structure, a window cleaning element fixed to the outer free end of one of said arms, a second window cleaning element carried on the outer free end of the other arm in opposed relation to the fixed cleaning element and mounted on the arm for movement toward and away from the fixed element, a handle secured to said movable cleaning element and having a portion thereof cooperating with the adjacent arm to form a hand grip, said handle and said portion of the arm acting to thrust the movable cleaning element toward the fixed cleaning element when tightly gripped by the hand, and means yieldingly resisting such movement of the movable cleaning element.

2. A window cleaning device comprising, in combination, a pair of arms extending in spaced generally parallel relation to one another and joined at one of their ends to form a U-shaped supporting structure, a window cleaning element fixed to the outer free end of one of said arms, a second window cleaning element carried on the outer free end of the other arm in opposed relation to the fixed cleaning element and mounted on the arm for movement toward and away from the fixed element, a handle secured to said movable cleaning element and having a part thereof extending in slightly spaced substantially parallel relation to the free end of the arm upon which the movable cleaning element is carried and cooperating with the latter to form a hand grip, said hand grip adapted when squeezed by hand to bodily move the movable cleaning element relative to the holder and toward the fixed cleaning element, means yieldingly resisting such movement of the movable cleaning element, and a releasable locking detent carried by the arm upon which the movable cleaning element is mounted and engageable with the handle to lock the element in the tightly gripped hand position.

3. A window cleaning device comprising, in combination, a pair of cleaning elements adapted to be positioned on opposite faces of a glass pane,

a substantially U-shaped holder for supporting and connecting said cleaning elements, one end of said holder being rigidly connected to one of said cleaning elements, the other end of said holder having a loose connection with the other 5 cleaning element and providing limited movement thereof toward and away from the rigidly connected cleaning element, and a handle secured to said movable cleaning element and having a part thereof extending substantially parallel to 10 but slightly spaced from the adjacent end of the holder and cooperating with the latter to form a hand grip, said part and the adjacent end of the holder when tightly gripped by the hand of the operator adapted to bodily move the movable 15 cleaning element relative to the holder and toward the other cleaning element to cause the two elements to compressively engage the opposite sides of a glass pane.
